UNITED STATES PATENT OFFICE.

JAMES HENRY C. BOIG, OF OKLAHOMA, OKLAHOMA.

DESIGN FOR A COTTON-PICKING NOZZLE.

52,508.

Specification for Design.

Patented Oct. 1, 1918.

Application filed November 8, 1917. Serial No. 200,985. Term of patent 14 years.

To all whom it may concern:

Be it known that I, JAMES HENRY C. BOIG, a citizen of the United States, residing in Oklahoma, Oklahoma county, Oklahoma, have invented a new, original, and ornamental Design for Cotton-Picking Nozzles, of which the following is a specification, reference being had to the accompanying drawings, forming a part thereof.

Figure 1 is a side elevation of a cotton picking nozzle, showing my design.

Fig. 2 is a front end view thereof, and
Fig. 3 is a rear end view thereof.

I claim—

The ornamental design for a cotton picking nozzle, as shown.

JAMES HENRY C. BOIG.
